UNITED STATES PATENT OFFICE.

IRA W. HOLLETT, OF CHICAGO, ILLINOIS, ASSIGNOR TO THE SEFTON MANUFACTURING COMPANY, OF ANDERSON, INDIANA, A CORPORATION OF INDIANA.

PAPER RECEPACLE.

1,082,868.

Specification of Letters Patent.

Patented Dec. 30, 1913.

Application filed August 2, 1909. Serial No. 510,774.

To all whom it may concern:

Be it known that I, IRA W. HOLLETT, a citizen of the United States, residing at Chicago, in the county of Cook and State of Illinois, have invented certain new and useful Improvements in Paper Receptacles, of which the following is a specification.

My invention relates to paper receptacles or vessels intended for the packaging of various articles and the object thereof is to provide a novel and advantageous construction of such a vessel, particularly as regards the means for securing the vessel in closed condition and for also attaching the ends of the carrying bail.

Other features of advantage and utility in my new construction of paper vessel will be apparent from the description hereinafter given.

20 In the drawings Figure 1 is a plan view of a blank from which the paper vessel is formed; Fig. 2 an enlarged vertical section on the line 2—2 of Fig. 9; Fig. 3 a perspective of the paper vessel in assembled condition just before being closed; Figs. 4 and 5 enlarged detail sections of the upper portion of the paper vessel illustrating different positions of the parts; Figs. 6 and 7 perspective views of one of the so-called 25 fastening tins; Fig. 8 a perspective of the paper receptacle as being set up or assembled from the blank illustrated in Fig. 1 before the fasteners, etc., are applied; Fig. 9 a perspective of the paper vessel in its complete and closed form; Fig. 10 a perspective view similar to Fig. 8 but illustrating a modified form of paper vessel; Fig. 11 a perspective of a portion of a paper vessel illustrating a modified form of fastening device; Fig. 12 a detail sectional view of the fastening device illustrated in Fig. 11; Fig. 13 a perspective similar to Figs. 8 and 10 but illustrating an additional modification; Fig. 14 a perspective of a portion of the paper receptacle 30 of Fig. 13 and illustrating a modified form of fastening device; Fig. 15 a detail sectional view of such fastening device; Fig. 16 a perspective of another modified form of paper vessel before having the fastening devices and bail applied; and Fig. 17 a perspective of such paper vessel in its complete and closed condition.

Referring to the embodiment of my invention in the form of paper receptacle or vessel

illustrated in Figs. 1 to 9 which represents my preferred form of construction, the receptacle is made from the blank shown in Fig. 1, the same comprising the bottom 1, pairs of side walls 2, 2 and 3, 3 hinged to such bottom and pairs of corner folds 4, 5 together with extensions and flaps hinged to the outer edges of said side walls and corner folds. As shown triangular portions 6, 6 are formed by means of oblique score lines 3^a at the outer ends of the side walls 3 and such triangular portions are each provided with hinged extensions or flaps 6^a separated by the score line 6^b. The opposite side walls 2, 2 are provided with hinged extensions 2^a and likewise the corner folds 4 and 5 are all provided with hinged extensions 4^a and 5^a respectively. In addition one of the corner fold extensions 5^a is provided with a hinged flap or tongue 7 and the similar corner fold extension at the diagonal corner of the blank 75 is provided with a flap or tongue 8. The extensions on the upper portion of the blank shown in Fig. 1 is provided with slots 9 for the purpose of receiving the fastening device at the central portion of the completed 80 receptacle while the extensions at the lower portion of such blank is provided with slots 10 for the purpose of receiving the pair of end tins which as hereinafter described serve not only to hold the receptacle closed but 85 also provide pivotal connection for the ends of the bail. The extensions on the upper portion of the blank of Fig. 1 are also provided with openings or short slots 11 for a purpose hereinafter made apparent. It will 90 be understood that when the paper receptacle is erected into receptacle or vessel form the slots 9, 10 and 11 will coincide with each other respectively. By preference portions of some of the extensions 4^a 95 are cut away in order to reduce the number of thicknesses of paper at the upper middle portion of the receptacle where the center, fastener tin is attached.

The blank being formed as described the 100 paper vessel is formed or erected therefrom into the shape illustrated in Fig. 8, the receptacle being in the present instance of a satchel form. The so-called fastening tins which are here of novel construction are 105 thereupon applied. As herein shown and by preference there are three of these tin fasteners, the two end ones thereof being iden-

2

tically the same but the middle one being slightly different. The construction of these end tins is shown in Figs. 6 and 7, the same consisting of a strip 12 of tin or the like with one end 12^a bent and passed through the slots 10 which register with each other when the blank is erected into vessel or receptacle form as shown in Fig. 8. The fastener tin is also provided with a longitudinally extending tongue 12^b which fits over the upper edges of the various extensions which are brought together adjacent said slots 10 and extends downwardly upon the inner face of the extension or flap 2^a. In addition the tin is provided with a projection struck from the tin itself as a tongue 12^c which when the body of the tin is bent over the extensions at the opposite side of the paper vessel engage into the series of short slots or holes 11 in the manner clearly indicated in Fig. 5 with the result that the various extensions of the paper receptacle when brought together as shown in Fig. 9 are secured in such condition and with the further result that the sides of the receptacle in which said short slots 11 are provided are prevented from sagging from the weight of the others or otherwise, owing to the engagement of the tongues 12^c into said slots.

30 As hereinbefore stated the end fastening tins provide for the pivotal connection of the ends of the bail and to this end the looped ends of the bail 13 are passed over the tins before the latter are bent in place by the user of the receptacle after the same has been filled with its contents. In this manner the end fastening tins have a double function, first that of securing or fastening the receptacle in closed condition and second that of providing pivotal connection for the bail.

35 By preference the receptacle is provided with a center fastening device consisting of a fastening tin 14 similar to the tin 12 but unprovided with the tongue 12^c, which tin is passed through the series of slots 9 to anchor the same into the extensions 2^a and 5^a of the receptacle with its tongue 14^a passed over the upper edges of such extensions and downwardly upon the inner face of an extension 2^a as clearly shown in Fig. 2 wherein, as will be understood, the thickness of the extensions as well as of the fastener is somewhat exaggerated for the purpose of a clear illustration. In practice the user or consumer bends the free end of the tin fastener over the upper edges of the extensions at the opposite sides of the receptacle. However, by preference the particular flap 5^a at the side of the receptacle to which the tin fastener 14 is anchored is provided with the flap or tongue 7 which is folded over the upper edges on both sides of the receptacle which are brought together as described and the free end of the tin

fastener is bent over such flap as shown in Fig. 2. This flap which can be conveniently provided without special addition of material serves to seal a considerable portion of the upper or outer edges of the extensions which are brought into juxtaposition when the receptacle is in closed condition as illustrated in Fig. 9. Also by preference another of the extensions 5^a is provided with the tongue or flap 8 which is tucked downwardly over an extension 5^a of the next adjacent corner of the receptacle and between such latter extension and the extension of its companion corner fold member 4^a, with the result that the corner folds associated with said flap 8 are held more securely in place adjacent its side wall 2. Thus by means of the peculiar fastening devices described the paper receptacle is not only securely held in closed condition but means are provided by the fasteners themselves for pivotally connecting the ends of the bail to such receptacle. Moreover, in respect to the paper receptacle described the fasteners, by reason of their engagement with the holes 10 in the extensions on one side of the receptacle, hold such side of the receptacle firmly in position and prevent it from sagging downwardly by reason of the weight of the contents or otherwise.

30 In Figs. 10, 11 and 12 I have illustrated another method of engagement between the fastening devices and one side of the paper receptacle. In the construction first described these fastening devices engaged in the holes 11 but in the modified construction I have substituted flaps 5^b which project over the upper or outer edges of the extensions 5^a and are adapted to be engaged by the tongues 12^c of the fastener tins in the manner clearly disclosed in Fig. 12. In other respects the construction is the same as that hereinbefore described and consequently the same reference characters are applied to the other parts.

35 Some measure of my invention may be obtained by omitting from the fastening tins the tongues 12^c, with the result that there will be no positive engagement between such contents and the side of the receptacle over which they are folded except that which is incident to such folding over of the tins and the clamping thereof against the sides of the box. Such modified construction is illustrated in Figs. 13, 14 and 15, in which the fastening tins 15 are the same as the tins 12 with the single exception of the omission of the tongues 12^c. When this form of fastening tins is employed I prefer to provide the extensions 5^a to which such tins are anchored with extension flaps 5^c which, in the operation of fastening the tins in place, are folded over the upper edges of the extensions of the receptacle. In this modified construction the tongues 15^a, which correspond with

the tongues 12^b of the other fastener, pass through the slots or holes 5^d at the base of the flaps 5^e. As in the other described constructions the bail 13 is pivoted at its ends to the fastening tins. The receptacle is also provided at its central portion with a flap 5^e proceeding from one of the extensions 5^a to which the central fastening tin 16 is anchored. By preference this tin is provided

10 with a tongue 16^a which extends through the slot or hole 5^c at the base of the flap 5^e and engages over the opposite extension 5^a over which such flap 5^e is folded in the operation of bending the fastening tin 16 in place.

15 This tongue 16^a serves to securely hold the extensions 5^a together at their upper edges, while the flap 5^e in conjunction with the other two flaps 5^e serves to close and seal the upper edges of said extensions along

20 their entire length. This modified form of construction of Figs. 13, 14 and 15 embodies all of the features of advantage of the other constructions already described with the exception that one side of the receptacle

25 not being positively engaged with the fastening tins is not securely held against sagging, especially if the contents of the receptacle are of considerable weight.

For paper receptacles of larger capacity than those hereinbefore described I prefer to provide additional fastening tins similar to the center fastening tin 14 and to also provide additional flaps adjacent to such particular fastening tins. For instance, as

35 shown in Figs. 16 and 17, which represent a paper receptacle of larger capacity than those already described, I have shown a series of three of said fastening tins 14, one of the same remaining at the central portion as

40 heretofore and the other two being arranged near the ends of the receptacle. The particular extensions 5^a to which all of these fastening tins 14 are anchored are provided with flaps 5^e similar in manipulation and

45 function to the flaps 5^e hereinbefore described, these fastening tins being likewise provided with tongues similar to the tongues 16^a already referred to, which tongues pass through the slots or openings 5^c. In this

50 modified construction the other fastening tins 12, which may be of any of the varieties described, serve both to close the receptacle and to provide means for the pivotal connection of the bail 13. In this form of receptacle

55 also practically the entire upper line of the receptacle is held closed and sealed by the flaps 5^e; since they cover all those portions of the edges of the flaps where there is any liability of the flaps spreading apart.

60 I claim:

1. In a paper receptacle having side walls provided with upstanding extensions brought together at the top along a central line to effect a closure, the combination, with

65 the receptacle body and a bail, of a pair of

fastening tins, one end of each of which is anchored to the upstanding extensions on one side of the receptacle, and the other end of which is foldable downwardly over the upper edges of the upstanding extensions on the other sides, the bail being pivoted to the intermediate portions of such tins.

70

2. In a paper receptacle having side walls provided with upstanding extensions brought together at the top along a central line and tending to spring apart, the extensions on one side being provided with openings, the combination, with the receptacle body and a bail, of a pair of fastening tins, one end of each of which tins is anchored to the upstanding extensions on the side opposite those provided with openings, and the other end of which is foldable downwardly over the upper edges of all the extensions and is provided with inwardly projecting tongues adapted to make spring engagement in said openings, the bail being pivoted to the intermediate portion of such tins; substantially as described.

75

3. In a paper receptacle having side walls provided with upstanding extensions brought together at the top along a central line to effect a closure, the combination, with the receptacle body and a bail, of a pair of fastening tins, one end of each of which is anchored to the upstanding extensions on one side of the receptacle, and the other end of which is foldable downwardly over the upper edges of the upstanding extensions on the other side and provided with means of engagement with the extensions on such latter side, the bail being pivoted to the intermediate portions of such tins.

80

4. In a paper receptacle having side walls provided with upstanding extensions which swing inwardly and downwardly in circular arcs to meet together at an angle along a central line to effect a closure of the box, a plurality of fastening devices arranged in alternate order on the opposite extensions, each device consisting of a malleable metallic strip anchored at one end to its extension and arranged to be bent downwardly over the opposite extension into position to interfere with its opening movement.

85

5. In a paper receptacle having side walls provided with upstanding extensions which swing inwardly and downwardly in circular arcs to meet together at an angle along a central line to effect a closure of the box, and in combination with a bail, a plurality of fastening devices arranged in alternate order on the opposite extensions, each device consisting of a malleable metallic strip anchored at one end to its extension and arranged to be bent downwardly over the opposite extension into position to interfere with its opening movement, the bail being pivoted to two of such devices.

90

95

100

105

110

115

120

125

130

6. In a paper receptacle having side walls provided with upstanding extensions which swing inwardly and downwardly in circular arcs to meet together at an angle 5 along a central line to effect a closure of the box, and in combination with a bail, the extension on one side having a flap foldable downwardly over the top edge of the extension on the opposite side to close the same, a 10 malleable metallic strip anchored at one end to the extension bearing the flap adjacent the base of the latter and arranged to be bent downwardly over said flap and underlying extension, and a pair of fastening devices 15 consisting each of a malleable metallic strip anchored at one end to the extension opposite that bearing the flap, said pair of fastening devices being adapted to be bent downwardly over the extension bearing 20 the flap into position to interfere with the opening movement of such extension and to

form at the bending point supporting bearings for the bail.

7. In a paper receptacle having side walls provided with upstanding extensions 25 which swing inwardly and downwardly in circular arcs to meet together at an angle along a central line to effect a closure of the box, one of said extensions having a flap foldable downwardly over the top edges of 30 the other extension to close and seal the same, a fastening device consisting of a malleable metallic strip anchored at one end to the extension bearing the flap adjacent the base of the latter and arranged to be bent 35 downwardly over such flap and underlying extension into position to interfere with the opening movement of such extension.

IRA W. HOLLETT.
